UNITED STATES PATENT OFFICE.

MARTIN FISCHER, OF ZURICH, SWITZERLAND, ASSIGNEE TO MOTOR AND GEAR IMPROVEMENT COMPANY, A CORPORATION OF NEW YORK.

ENGINE.

1,164,610.

Specification of Letters Patent. Patented Dec. 14, 1915.

Application filed March 21, 1914. Serial No. 826,177.

To all whom it may concern:

Be it known that I, MARTIN FISCHER, a citizen of Switzerland, and a resident of Zurich, in the Canton of Zurich, Switzerland, have invented certain new and useful Improvements in Engines, of which the following is a specification, reference being had to the drawings hereto attached and made a part hereof.

10 My invention relates to engines and more particularly internal combustion engines, or such in which the conditions requiring valves and valve control require special construction for improved conditions of operation of the engine.

Among the objects of my invention are to produce a structure to effect more perfect operation of slide valves in internal combustion engines, as well as to insure reliability, noiseless operation and other advantages as will hereinafter appear.

I have heretofore filed application for United States patent Jan. 12, 1912, Ser. No. 670,904, in which I have shown a construction containing the essential elements of an engine, and of which the present invention is an improvement or modification. In particular, by the present improvement, I produce a structure still further insuring the uniform and accurate control of the slide valves as hereinafter described.

While the invention is particularly set forth in the claims hereto annexed I have shown one form of embodiment of my invention in the accompanying drawings, in which—

Figure 1 is a section of an engine through the longitudinal axis of the cylinder. Fig. 2 is a transverse section of the cylinder at 2—2 of Fig. 1. Fig. 3 is a section at 3—3 of the lower end of the slide valve.

In the drawings, A is a cylinder; B a cylinder head; C is a projection on the cylinder head or reentrant ring; D is a packing ring on the projection C, which may be termed a junk-ring; E, E are slide valves having ports F, F through the upper ends and openings G, G in the lower ends. In the head B, is a spark plug surrounded by a tubular upward projection H of head B, passing through an opening in a head jacket J, and having a locking nut or ring K. The head is fastened to cylinder proper by bolts with nuts as shown, or any other desired manner, while the head-jacket J, in-

closes the head proper B, thereby forming the water jacket space around the head or combustion chamber of the cylinder.

The piston L, with connecting rods and crank shaft, are in any desired form, and operate so that the piston supports the valves E, E, on their inner face pressing them into the recesses M, M. Ports N, N, form a passage through the cylinder wall to the recesses M, M opposite the upper ends of the slide valves E, E, while the openings F, F, in the valves are arranged to periodically register with the port openings.

The ring projection C, on the head extends into the upper end of the cylinder, or 70 extends over the end of the valves E, E to such an extent as to support the upper ends of the slide valves. The junk-ring D is so arranged that the upper end of slide valves E, E, will engage it and be held in place in 75 the recesses M, M, respectively, at their upper ends.

By this construction it will be seen that the slide valves which are let into recesses at the sides of the piston, are held in these 80 recesses not alone by the piston, but their upper ends are also held in place by the projection or reentrant ring on the head of the cylinder, or by the junk ring placed on the outer side of this reentrant ring. In this 85 manner I securely hold and can with accuracy predetermine the proper seating of the valves and prevent any unnecessary motion or any vibration.

At the lower end of each slide valve a bell 90 crank or other operating mechanism is connected with the opening G, at the foot of the valve by means of a block P, held in bracket R, of the bell crank arm. In this manner the block which is well oiled owing to its position in the interior of the crank case and its proximity to the cylinder, will have free play by sliding back and forth in the opening G while the bell crank arm reciprocates.

It will be apparent that modifications in 100 dimension or detail or arrangement may be made without departing from my invention, but

What I claim and desire by Letters Patent is;—

1. In an internal combustion engine, a cylinder, a cylinder head, an extension to said head projecting into the cylinder, a piston reciprocating in said cylinder, a recess in the wall of the cylinder, a slide valve 110

adapted to slide in said recess longitudinally of the cylinder, and a portion of the projection from the head adapted to engage the inner side of the slide valve to hold the end thereof in the recess.

2. In an internal combustion engine, a cylinder, a piston, a recess in the side of the cylinder, a slide valve in said recess engaged by said piston, a reentrant projection at the head end of said cylinder extending therein to an extent to engage only by an arc of its circumference the end of said slide valve and hold it in the recess, another arc of the circumference of said reentrant projection being opposed to the inner wall of the cylinder proper without the intervention of any moving part.

3. In an internal combustion engine, a cylinder, a piston reciprocating in the cylinder supported by the walls of the cylinder, a recess or depression through part of the circumference of the cylinder, a valve adapted

to reciprocate in said recess, a projection or ring extending inwardly from the end of said cylinder and a packing member on the outer side of said extension adapted to engage said slide valve and hold it in position in the recess.

4. In an internal combustion engine, a cylinder, a port near the end of said cylinder, a slide valve adapted to open and close said port, an opening in said slide valve to register with said port, a projection from the head of the cylinder engaging the inner side of said slide valve and extending to a point opposite the edge of said port.

In testimony whereof, I have signed my name to this specification, in the presence of two subscribing witnesses, this 24th day of February, 1914.

MARTIN FISCHER.
